(57) **CLAIM**

The ornamental design for a T-slot router bit as shown and described.

DESCRIPTION

FIG. 1 is a front, top, right side elevation view of a T-slot router bit in accordance with our design;

FIG. 2 is a front elevation view of the T-slot router bit as shown in FIG. 1;

FIG. 3 is a rear elevation view of the T-slot router bit as shown in FIG. 1;

FIG. 4 is a right side elevation view of the T-slot router bit as shown in FIG. 1;

FIG. 5 is a left side elevation view of the T-slot router bit as shown in FIG. 1;

FIG. 6 is a top plan view of the T-slot router bit as shown in FIG. 1; and,

FIG. 7 is a bottom plan view of the T-slot router bit as shown in FIG. 1.

The claimed design is shown with a symbolic break in its length. The appearance of any portion of the article between the break lines forms no part of the claimed design.

1 Claim, 4 Drawing Sheets
